Primary Examiner—Doris V. Coles*Assistant Examiner*—Linda Brooks*Attorney, Agent, or Firm*—Elsie C. Turner**[57] CLAIM**

The ornamental design for a storage and display module for ceiling fixture downrods, as shown and described.

DESCRIPTION

FIG. 1 is a perspective view of a storage and display module for ceiling fixture downrods showing my new design, shown broken away in the middle to indicate indeterminate length, it being understood that the contours repeat uniformly along its length, with ends of three downrods shown in broken lines for purposes of illustration only and forming no part of the claimed design.

FIG. 2 is a plan view of the closed end thereof;

FIG. 3 is a plan view of the open end thereof;

FIG. 4 is a side elevation view of FIG. 1, it being understood that the other three sides are identical; and,

FIG. 5 is a perspective view of a second embodiment of FIG. 1, the only differences being the increased number of cylinders and their decreased width, it being understood that all the other surfaces are the same as the first embodiment shown in FIGS. 1-4, with ends of three downrods shown in broken lines for purposes of illustration only and forming no part of the claimed design.
